Fig. 9

Fig. 10

FIG. 1 is a perspective view of a trolling lure showing our new design;

FIG. 2 is an end elevation as seen from the left of FIG. 1;

FIG. 3 is a side elevation as seen from the side opposite that shown in FIG. 1;

FIG. 4 is a top plan view;

FIG. 5 is a bottom plan view of FIG. 4;

FIG. 6 is a perspective view of another embodiment of a trolling lure showing our new design;

FIG. 7 is an end elevation as seen from the left side of FIG. 6;

FIG. 8 is a side elevation as seen from the side opposite that shown in FIG. 6;

FIG. 9 is a top plan view of the trolling lure shown in FIG. 6; and

FIG. 10 is a bottom plan view thereof.

The broken lines in FIG. 1 are for illustrative purposes only.

This is a continuation-in-part of design application Ser. No. D. 13,830, filed Oct. 3, 1968 and now abandoned.

We claim:

The ornamental design for a trolling lure, as shown and described.
